TABLE TYPE STAPLER

Frank S. Boroughs, New York, N. Y., assignor to
 Arrow Fastener Co., Inc., Brooklyn, N. Y., a corporation of New York

Application August 20, 1949, Serial No. 111,413

2 Claims. (Cl. 1-3)

1

This invention relates to table staplers.

An object of this invention is to provide a stapler comprising a base, staple magazine pivoted to one end of the base, and cover pivoted at its rear end to the rear end of the staple magazine and swingable relative to the magazine and the base, means on the cover to drive staples from the magazine against an anvil on the base, and spring operated latch means to locate the degree of angular movement of the cover relative to the staple magazine, said latch means being releasable to permit the cover to be swung upwardly away from the staple magazine so as to uncover the top of the staple magazine to permit servicing thereof.

Another object of this invention is to provide in a stapler of the character described, a cover, an angle shaped member attached to the underside of the cover and having a downwardly extending finger, and a driver blade removably mounted on said finger, and adapted to drive staples from the staple magazine, said blade being attached to the said finger without any screws, rivets, welding or any other permanent attaching means.

Yet a further object of this invention is to provide in a stapler of the character described, a staple magazine pivoted at its rear end to the rear end of the base, and spring bumper or shock absorber means to cushion downward movement of the magazine toward the base and to lift the magazine relative to the base when downward pressure is removed from the cover of the stapler.

Yet another object of this invention is to provide a table type stapler of the character described comprising a staple magazine comprising a body having upwardly extending side walls, a staple guide within said body, a pusher slidably disposed within said body, a push rod slidably engaging the pusher, a back member riveted to the rear end of the push rod, a latch having rocking engagement with the back member and formed with a tongue contacting the inner surface of the back member, said tongue having an opening through which the push rod passes, a coil compression spring on the push rod interposed between the tongue and the pusher, and said latch having means to engage appropriate hooks in the side walls of said body for retaining the push rod on the staple magazine, said push rod, back member and rocking latch being movable forwardly to disengage the latch from the hooks on the side walls of the body to permit removal of the pusher and push rod from the stapler.

2

A still further object of this invention is to provide in a stapler of the character described a cover pivoted to the staple magazine, a holder for a driver blade riveted to the top wall of the cover, a spring for causing relative movement between the staple magazine and cover, likewise riveted to the top wall of the cover and a plate welded to the upper surface of the top wall of the cover and being formed with an upwardly recessed portion to receive the heads of the rivets which rivet blade holder and spring to the cover.

Yet another object of this invention is to provide a device of the character described in which the back member of the pusher mechanism has rails slidably received in tracks formed in side walls of the staple magazine body for guiding the back member relative to the staple magazine.

Yet a further object of this invention is to provide a small, compact, rugged table type stapler of the character described, which shall be smooth and positive in operation, easy to assemble and clean and service, and which shall yet be practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawings in which is shown various illustrative embodiments of this invention,

Fig. 1 is a side elevational view of the stapler embodying the invention;

Fig. 2 is a longitudinal cross sectional view thereof;

Fig. 3 is a top plan view of the stapler with parts broken away and in cross section;

Fig. 4 is a cross sectional view taken on line 4-4 of Fig. 2;

Fig. 5 is a cross sectional view taken on line 5-5 of Fig. 2;

Fig. 6 is a cross sectional view taken on line 6-6 of Fig. 2;

Fig. 7 is a cross sectional view taken on line 7-7 of Fig. 2;

Fig. 8 is a cross sectional view taken on line 8-8 of Fig. 2;

Fig. 9 is a rear elevational view of the staple device;

Fig. 10 is a perspective view of the latch for the pusher mechanism;

Fig. 11 is a perspective view of the back member forming part of the pusher mechanism;

Fig. 12 is a cross sectional view taken on line 12—12 of Fig. 2;

Fig. 13 is a cross sectional view taken on line 13—13 of Fig. 12;

Fig. 14 is a front view of the driver blade holder; and

Fig. 15 is a partial front view of the driver blade.

Referring now in detail to the drawing, 10 designates a stapler embodying the invention. The same comprises generally a base 11, a staple magazine 12 pivoted thereto and a cover 13 pivoted to the staple magazine.

The base 11 comprises a member 14 made of sheet metal and having a top wall 15 from which extend downwardly, rearwardly converging flanges 16 interconnected by a front semi-circular flange 17. Flanges 16 terminate forwardly of the rear end of the base, as at 18. At the rear end of the wall 15 is a rearwardly extending tongue 19 from which extend upwardly a pair of parallel side walls or flanges 20. Flanges 20 are formed with aligned openings 21 for the purpose hereinafter appearing.

The tongue 19 is formed with a central opening 21 (Fig. 2) disposed between the side flanges 20 for the purpose hereinafter appearing.

The side flanges 20 extend rearwardly beyond the tongue 19 as shown in Fig. 2 of the drawing. The flanges 20 may have upper, downwardly and rearwardly curved edges 22. The top wall 15 is formed, rearwardly of its front edge, with a depressed portion 23 to receive an anvil 24, of usual construction, fixed thereto in any suitable manner. The tongue 19 may also be formed with downwardly depressed rib 25 to stiffen the tongue.

Extending through the opening 21 in the tongue 19 is a pin 26 having a portion 27 of enlarged diameter contacting the upper surface of the tongue 19. Extending downwardly from portion 27 is a portion 28 of reduced diameter, which passes through the opening 21, and the same has a rivet head 29 at its lower end. The portion 27 has a rivet head 30 at its upper end.

Contacting the underside of the tongue 19 is a rubber pad 31 extending below the lower edges of the flanges 16, 17. The pad 31 is formed at its underside with a central recess 32 and with a through opening 33, centralized with respect to the recess 32 and registering with the opening 21. The portion 28 passes through the opening 33. Within the recess 32 is a washer 34 contacting the undersurface of said recess and held in place by the rivet head 29. Mounted on top of the tongue 19 is a spiral coil spring 38, the coils of which decrease in diameter toward the top. On the top coil is a washer 39 contacted by the rivet head 30 of the pin 26. The rivet head 30 thus limits upward movement of the washer 39 but permits the washer to be depressed for compressing the spring 38. The purpose of this spring will be explained hereinafter.

Extending through openings 20a in the flanges 20 is a pivot pin 40 having rivet heads 41a (Figs. 2 and 8) contacting the outer surfaces of said flanges. The staple magazine 12 as will appear hereinafter is pivoted to the pivot pin 40.

Said staple magazine 12 comprises a magazine body 41 having a bottom wall 42 and upwardly extending side walls 43. The bottom wall terminates forwardly of the rear ends of the side walls, as at 44. The rear ends of the side walls have downwardly extending ears 45 contacting the inner surfaces of the flanges 20. The ears 45

have bearing openings 46 through which the pivot pin 40 passes. Said bottom wall 42 has an opening 47 forwardly of the rear edge 44 and concentric with the washer 39 but of smaller dimension than said washer. It will now be understood that should the staple magazine be swung downwardly, or in a counterclockwise direction, looking at Fig. 2, the bottom wall 42 of the staple magazine body 41 will contact the washer 39 and compress the spring 38. When pressure is released from the staple magazine said spring 38 serves to lift the staple magazine. When the staple magazine is depressed the upper end of the pin 26 projects through the opening 47 into the staple body.

The side walls 43 of the staple body have longitudinal inwardly pressed ribs 50 forming outer channels or tracks 51 for the purpose hereinafter appearing.

20 The bottom wall 42 terminates in an edge 52 rearwardly of the forward edges of the side walls 43. Said bottom wall 41 furthermore, has upwardly recessed portions 54 for the purpose hereinafter appearing.

25 The side walls 43 of the body are formed with notches 55 (Fig. 2) forwardly of the front edge 52 of the bottom wall 42, and said side walls have downwardly extending wings 56 forwardly of the notches 55 extending to the plane of the underside of wall 42. Extending upwardly from said channel shaped ribs 50 are side walls 57 (Fig. 2) having upper edges 58. At the front end of the magazine, the side walls 57 extend higher than edges 58 forming edges 59 and extending 35 inwardly from the edges 58 toward each other are top flanges 60 (Figs. 2 and 5) for the purpose hereinafter appearing.

Extending upwardly from the side walls 57 of the magazine body 41 and rearwardly of the flanges 60, are hooks 61 formed with undershoulders 62. Extending downwardly from the shoulders 62 are edges 63 forming notches 64. The notches 64 have lower edges 65 disposed at a lower level than the edges 58. Extending 45 upwardly from the rear ends of the edges 65 are edges 69 forming the rear ends of the notches 64. Extending rearwardly from the upper ends of the edges 69 are edges 70 from which extend upwardly edges 71 forming notches 72 extending forwardly from the edges 71 and undershoulders 73 from which extend upwardly edges 74. Extending rearwardly from the upper ends of the edges 74 are edges 75 which are at a higher level than the edges 58 but may be somewhat below the upper ends of the hooks 61. The edges 75 extend to the rear ends of the side walls 57 and extending downwardly therefrom are edges 76.

In the upper rear corners of the side walls 57 of the magazine body 41 are aligned bearing openings 77 for the purpose hereinafter appearing.

Attached to the front end of the body 41 is a front fixed cover 80 having a front wall 81 and side walls 82. The upper end of the wall 81 is curved upwardly and forwardly to form a lip 81a for the purpose hereinafter appearing. The side walls 82 contact the outer surface of the side walls 43, 57 of the body and are either riveted or welded or otherwise attached thereto. The front wall 80 is spaced from the front edges of the side walls of the magazine body, thereby forming a track 82 for a plunger blade 84, which will be described in greater detail hereinafter.

Within the magazine body 41 is a staple guide 90. Said guide 90 comprises a top wall 91 spaced

somewhat below the channel ribs 50. Extending downwardly from the top wall 91 are side walls 92 contacting the upper surface of the bottom wall 42 of the staple body 41. Cut from the top wall 91 are downwardly depressed tongues 94 contacting the upwardly recessed portions 54 of the bottom wall 42. The tongues 94 are riveted to said upwardly recessed portions 54 as by 95.

The side walls 92 of the staple guide 90 are spaced inwardly from side walls 43 of the magazine body and form therewith a chamber to receive a staple strip S which may move forwardly toward the track 82. The side walls 92 extend to the plane of the forward ends of the side walls 43 of the magazine body so that the forwardmost staple in the staple strip S may be depressed by the plunger 84. At the forward end of the staple guide, the side walls have wings 96 which extend down to the plane of the undersurface of the bottom wall 42. Said wings 96 contact the forward edge 52 of the bottom wall 42. Flaps of metal 56a from the side walls 81 and 82 of the front fixed cover 80 are pushed into notches 55 and forwardly of front edge 52.

Mounted on the staple guide is a pusher mechanism 100. Said pusher mechanism comprises a channel shaped pusher member 101 having a top wall 102 and downwardly extending flanges 103. The top wall 102 contacts the top wall 91 of the staple guide 90 and flanges 103 disposed between the side walls 92 of the staple guide and the inner surfaces of outer walls 43 of the magazine body 41. Extending upwardly from the top wall of the pusher are apertured parallel ears 103a, 104 and 105. The ear 103a is at the front end of the pusher; the ear 104 is between front ear 103 and the rear ear 105. Extending through the aperture in the ear 105 is a horizontal push rod 106 riveted at its front end. Riveted to the rear end of the push rod, as at 107, is the back wall 108 of a back pusher member 109. Said back wall 108 is formed with an opening through which the reduced neck of the push rod passes. Extending forwardly from the rear wall 108 (Fig. 11) of the back member 109 are side walls 110. Said side walls are formed at their upper ends with upwardly extending lugs 111. Extending forwardly from the side walls 110 are rail members 112 adapted to slidably engage within the channels 51 of the body.

Rockingly mounted on the back member 109 is a latch member 113. Said latch member 113 comprises a top wall 114 formed with slots 115 receiving the lugs 111 and contacting the upper edges of the side walls 110 and rear wall 108 of said back member. Cut from the top wall 114 is a downwardly extending tongue 116 contacting the inner surface of the back wall 108. At the lower end of the tongue 116 is a hole 117 through which is loosely received the push rod 106, thereby permitting rocking movement of member 113 relative to the back member 109 about the lugs 111. The top wall 114 is adapted to contact and overlie upper edges 75 of the side walls 57 of the magazine body. Extending downwardly from the front end of the top wall 114 are parallel flanges 118 from which extend outwardly, wings 119 having rearwardly extending ends 120 engaging within the notches 72 (Fig. 2). Said edges 120 thus engage the end edges 73 of the side walls 57 to retain the entire pusher mechanism 100 against rearward movement.

Normally, the back wall 108 is spaced from the rear ends of the staple body and staple

guide. When it is desired to remove the pusher mechanism 100, pressure is exerted forwardly against the back member 109 so that the entire pusher mechanism is pushed forwardly to release extending ends 120 of the latch member from the undershoulders 73. The latch member 113 may then be rocked about the lugs 111 in a clockwise direction, looking at Fig. 2 of the drawing. The entire latch mechanism including members 109, 113, and rod 106 and the pusher 101, may then be pulled rearwardly and out of the staple magazine. Received on the pusher rod 106 but between the ear 105 and the tongue 116 is a coil compression spring 121 which normally tends to rock the latch device 113 in a counterclockwise direction, looking at Fig. 2 of the drawing, to retain the latch in engagement with the magazine body. The spring also urges the pusher forwardly to press the staple strip toward the front cover 80.

The pivoted cover 13 comprises a member 125 which may be made of die pressed or stamped sheet metal. Said member 125 comprises a top wall 126 from which extend downwardly side walls 127. At the rear ends of the wall 127 are aligned apertures 128a which register with the opening 77 in the side walls 57 of the magazine body. Extending through the apertures 77, 128a is a pivot pin 129 having rivet heads 129a at the ends thereof contacting the outer surfaces of the side walls 127. The pivot pin 129 is located above the pivot pin 40 and somewhat forwardly with respect thereto. Extending forwardly from the side walls 127 are flanges 128b meeting on a bisecting plane and forming the front end for the pivoted cover member 125. The side walls 127 are formed with aligned slots 130, the upper edges of which are located normally at the level of the end edges 62 of the hooks 61. Said slots 130 extend rearwardly of the hooks 61, being located in the region of the notches 64. The lower rear edges of the side walls 127 are cut away as at 132 to by-pass the side flanges 20 of the base. The top wall 126 is formed with a pair of centrally aligned through openings 135 and 136 for the purpose hereinafter appearing.

Attached to the top wall 126 by means of rivet 137 passing through opening 135 is the top arm 138 of a holder 139 for the driver blade 84. The upper head of the rivet contacts the top surface of the wall 126. The lower end of the rivet contacts the underside of the arm 138.

Extending downwardly from the forward end of arm 138 is an arm 140 formed with a T-shaped slot 141 having a top wider portion 142 and a central downwardly extending neck portion 143. The metal from which the slot was cut is bent forwardly to form a T-shaped head 143 having a forward wide portion 144 and a rear narrow neck portion 145. The driver blade 84 has a T-shaped slot 146 having a lower wide portion 147 and an upwardly extending narrower neck portion 148. The wide portion 144 of the head 143 is passed through the wide portion 147 of the slot 146 and then the blade 84 is moved downwardly to bring the neck portion 145 upwardly into the neck 148 of the slot 146. The upper end of the blade 84 will then be flush with the upper side of portion 138 of holder 139 so that when arm 138 is riveted by means of rivet 137 to the top wall 126 of the cover, the blade will be retained by the cover against upward movement or disengagement from the arm 140. The wings of the wide portion 144 of said head

143 contact the blade 84 and serve to snugly hold said blade against the arm 140. The lower end of the arm projects into the track 82. When the cover is swung toward the staple magazine the forwardly and upwardly curved lip 81a serves as a guide to guide the lower end of the blade into the track 82 and against the inner surfaces of the front wall 81 of the cover 80.

Extending through the opening 136 in the top wall 126 of the cover is a rivet 150 which serves to rivet to the underside of the said top wall, a pair of strip springs 151 and 152. The riveted ends of the springs 151, 152 contact one another. The anchored end of the spring 151 overlies the anchored end of the spring 152. The lower head of the rivet 150 contacts the underside of the spring 152. The upper head of said rivet overlies the top of wall 126. The spring 152 has a downwardly and then upwardly curved free end 153 contacting inwardly extending flanges 60 on the body member 41 (Fig. 5) and tending to rotate the cover 13 away from the staple body member 41.

The upper spring 151 has a rearwardly extending portion 155 contacting the underside of wall 126 and extends downwardly from the rear end to form an extension 157 disposed rearwardly of the hook 61 and below the slots 130.

Extending through the slots 130 is a latch plate or bar 160. The latch 160 has outer end portions 161 which project beyond the slots 130. The rear edge of the latch plate or bar 160 is formed with a notch 162 (Figs. 2 and 3) within which the lower end 157 of the spring is received so as to prevent side movement or side shifting of bar 160.

The spring 157 normally presses the latch member 160 forwardly into engagement with the hooks 61, thus the upper surface of member 160 engages beneath the under shoulders 62 of said hooks. When member 160 engages the hooks 61 the cover member 13 may be moved in a counter-clockwise direction relative to the magazine 12. During such action the bar 160 contacting edges 63 will move downwardly within the notches 64 thereby deflecting the spring 152. When pressure is released from the pivoted cover, the spring 152 will raise the cover until the latch 160 contacts the undershoulders 62 to limit upward movement of the cover relative to the staple magazine.

To release the cover to permit the same to be swung all the way back, the ends of the bar 160 are gripped by two fingers of the user on extensions 161 (Fig. 3), and the bar is pulled back to disengage the bar from the hook 61, and then the cover may be swung all the way upwardly to uncover the top of the staple magazine to permit servicing, cleaning, removing jammed staples and the like. When the cover is swung downwardly again, the bar 160 will engage the downwardly and rearwardly inclined, or cammed or bevelled edges 61a at the top of the hooks, and said latch will be guided rearwardly against the same by spring 157 until it snaps beneath the hooks.

Welded to the top of the front end of the cover is a hand engaging plate 170. Plate 170 has downwardly extending side flanges 171 spaced outwardly from the side walls of the cover and it also has front downwardly extending flanges

172 spaced forwardly of the front wall 128 of the cover. Member 170 has a top wall 173 which overlies front portions of the top wall 126. Said top wall 172 may be formed with an upwardly recessed longitudinal rib 174 receiving the heads of the rivets 137 and 150.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention I claim as new and desire to secure by Letters Patent:

1. In a stapler, a magazine, a cover pivoted to said magazine, means on the cover to drive staples from the magazine, said magazine comprising a magazine body formed with upwardly and rearwardly extending hooks, a latch bar slid-
20 able on said cover engageable with said hooks and spring means on the cover to retain said latch bar in engagement with said hooks, said spring means comprising a strip spring having a front end fixed in the underside of the cover, and a rear downwardly extending face and en-
25 gaging the back of the latch bar and pressing the same forwardly to engage the rearwardly ex-
30 tending hooks on the magazine body.

2. In a stapler, a staple magazine, a cover piv-
35 oted thereto, said staple magazine being formed with a track through which staples may be ejected, a member attached to the cover and having a downwardly extending arm formed with a for-
40 wardly projecting T-shaped lug and a driver blade having a T-shaped slot, the neck portion of the lug passing through the neck portion of the slot, and the head of said lug holding the blade against said arm, and the upper end of said blade contacting the underside of said cover.

FRANK S. BOROUGHHS.
